ELASTIC RAIL SPIKE AND ITS ARRANGE-
MENT WITH RESPECT TO THE RAILSBerthold Kuckuck, New York, N. Y., assignor to
Elastic Rail Spike Corporation, New York,
N. Y., a corporation of Delaware

Application April 16, 1938, Serial No. 202,434

15 Claims. (Cl. 238—349)

My invention relates to improvements in elastic rail spikes and more particularly to the arrangement thereof with respect to the rails.

The application of elastic rail spikes usually requires relatively wide spacing between the sides of the rail flange and the lines of the spike holes, because the resilient gripping arm which projects transversely of the longitudinal rail axis must be relatively long in order to function properly, while the tips of the arms must be free to pass the sides of the rail head, as the spike is being driven into the tie. In many instances, this wide spacing of the spike holes from the rail flange is decidedly impractical.

It is the object of the present invention to provide a rail fastening in which the advantages of the long resilient gripping arm are retained and the wide spacing of the spike hole from the rail flange is obviated, while the tip of the gripping arm does not project inwardly beyond the plane coinciding with the adjacent vertical surface of the rail head.

A further object of my invention is to provide a rail fastening means which insures substantial resistance against lengthwise creeping of the rail.

I accomplish these objects by means of the combination in a resilient fastening for securing rails to ties of an elastic rail spike having a shank driven into a spike hole disposed adjacent the rail flange and a gripping arm resiliently engaging the flange of the rail and projecting towards the rail at an angle between 60° and 45° with respect to the longitudinal axis thereof with its free end pointing in the longitudinal direction opposite to that of the traffic.

My invention is illustratively exemplified in the accompanying drawings, in which

Fig. 1 is a perspective view of a rail fastening according to one embodiment of the present invention;

Fig. 2 is a perspective view of a spike with laterally twisted gripping arm;

Fig. 3 is a fragmentary top plan view of one embodiment of a tie plate;

Fig. 4 is a similar view of a further embodiment of a tie plate;

Figs. 5 and 6 are fragmentary top plan views of a tie plate according to Fig. 4, in combination with different types of spikes;

Fig. 7 is a top plan view of a plurality of rail fastenings, according to the present invention, as applied to a rail for unidirectional traffic; and

Fig. 8 is a top plan view of a plurality of

rail fastening applied to a rail arranged for traffic in both directions.

Referring now to Fig. 1, 10 denotes a wood tie, 11 the tie plate disposed on said tie, and 12 a rail, having a head 13, a web 14, and a flange 15, which rests on the tie plate 11. The tie plate 11 is provided at a point adjacent the rail flange 15, with a perforation 16 of the usual rectangular shape having two of its sides parallel to the longitudinal axis of the rail. 17 denotes the rail spike, which has a rectangular transverse cross-section and consists of a spring metal band bent upon itself to form two parallel strands, the spike comprising a straight shank 18 which passes through the perforation 16 of 15 the tie plate 11 and into a spike hole 19, which is disposed in the wood tie 10 and which is in alignment with the perforation 16, whereby the shank is secured against rotation in the latter. The upper portion of the spike is bent to form a 20 sidewardsly projecting resilient gripping arm 20, which is then twisted laterally about the vertical axis of the shank 18 (see Fig. 2) to project towards the rail 12 at an angle between 60° and 45° with respect to the longitudinal axis of the 25 latter. The tip 21 of the resilient gripping arm 20 engages the rail flange 15 at a point outside and free of the vertical plane coinciding with the adjacent vertical surface of the rail head 13, whereby the tip 21 of the gripping arm 20 is free 30 to pass the head 13 of the rail 12, as the spike 17 is driven into the spike hole 19, although the length of the resilient gripping arm 18 exceeds the distance between the spike hole 19 and said vertical plane.

Fig. 3 shows a tie plate 22 with a rectangular perforation 23, the sides of said perforation 23 being disposed at an oblique angle with respect to the longitudinal axis of the plate. In a tie plate of this type, a normal resilient spike may 40 be used, the same having a gripping arm projecting sidewardsly in the plane of the shank, and being inserted onto the spike hole with its shank secured against rotation in said perforation 23 and its gripping arm projecting towards the rail 45 at an oblique angle with respect to the longitudinal axis thereof.

The tie plate 24 according to Fig. 4 is provided with an octangular perforation 25 which may accommodate either a spike 26 having a 50 gripping arm 27 twisted laterally relative to the shank 28 (see Fig. 5), said spike being inserted into the perforation 25 with the shank faces parallel to the edges of the plate 24, or a normal spike 29, having its gripping arm 30 curved side- 55

wardly in the plane of the shank 31, the latter being inserted into the perforation 25 with its faces at an oblique angle relative to the plate edges.

5. Fig. 7 illustrates the application of rail fastenings, according to the invention, to a rail arranged for unidirectional traffic. In the embodiment shown, a tie plate according to Fig. 3 is used in combination with normal resilient spikes. All the gripping arms 32 are uniformly disposed with their free ends 33 pointing in the longitudinal direction opposite to that of the traffic (indicated by the arrow A). This arrangement has the particular advantage, that 10 the rail 34 is prevented from creeping lengthwise because any movement of the rail in the direction of the arrow A (see also Fig. 1) tends to turn the gripping arm towards the web of the rail. Owing to the upwardly inclined surface 15 of the rail flange, this tendency to turn results in a substantially increased pressure of the gripping arm on the rail during passing of a train, while thereafter, the returning gripping arm tends to restore the rail to its initial position.

20 25 Fig. 8 shows rail fastenings, according to the invention, applied to a rail arranged for traffic in both directions. In the embodiment shown in Fig. 8, spikes of normal construction are used in combination with tie plates of the type illustrated in Figs. 4 to 6 and pairs of spikes 35-36 are alternately disposed with the free ends of one pair 35 pointing in one longitudinal direction and the free ends of the following pair 36 pointing in the opposite longitudinal direction. In this arrangement, of course, each of the two groups offers increased resistance against lengthwise 30 35 creeping of the rail in one direction.

I claim:

1. In a rail fastening, the combination with a 40 wood tie and a rail supported thereon, of a rail spike comprising a shank driven into a vertical spike hole in said tie and a resilient gripping arm curved upwardly and sidewardly away from said shank and having its free end bent slightly 45 downwardly to engage the rail flange at a point spaced from said shank, the latter being held against rotation in an angular position in which said gripping arm projects at an oblique angle towards the rail with its free end pointing in the 50 longitudinal direction opposite to that of the traffic.

2. In a rail fastening, the combination with a 55 wood tie and a rail supported thereon, of a rail spike comprising a shank driven into a vertical spike hole in said tie and a resilient gripping arm curved upwardly and sidewardly away from said shank and having its free end bent slightly 60 downwardly to engage the rail flange at a point spaced from the shank a distance exceeding that 65 between the spike hole and the vertical plane coinciding with the adjacent vertical surface of the rail head, said shank being held against rotation in an angular position in which said gripping arm projects at an oblique angle towards the rail with its free end disposed outside of said 70 vertical plane.

3. The combination, as claimed in claim 1, in which said spike hole is disposed adjacent the rail flange.

70 4. In a rail fastening, the combination with a rail, a wood tie, and a tie plate disposed on said tie and having a center portion supporting the flange of the rail and a side portion provided with a perforation, of a rail spike comprising a 75 shank passing through said perforation into a

vertical spike hole in said tie and a resilient gripping arm curved upwardly and sidewardly away from said shank and having its free end bent slightly downwardly to engage the rail flange at a point spaced from said shank, and 5 interengaging means on said tie plate and shank, respectively, securing the latter against rotation in an angular position in which said gripping arm projects at an oblique angle towards the rail.

10 5. In a rail fastening, the combination with a rail, a wood tie, and a tie plate disposed on said tie and having a center portion supporting the flange of the rail and a side portion provided with a polyangular perforation, of a rail spike comprising a shank including a portion of substantially square cross-section and a resilient gripping arm curved upwardly and sidewardly away from said shank and then slightly downwardly, said shank passing through said perforation into a 15 vertical spike hole in said tie and being held in said perforation against rotation in an angular position in which said gripping arm projects at an oblique angle towards the rail with its free end 20 engaging the rail flange at a point spaced 25 from said shank.

6. In a rail fastening, the combination with a rail, a wood tie, and a tie plate disposed on said tie and having a center portion supporting the flange of the rail and a side portion provided 30 with a polyangular perforation, four corners of said perforation corresponding to the corners of an imaginary square having two of its sides disposed at right angles to the longitudinal axis of the rail, of a rail spike comprising a shank of 35 substantially square cross-section fitting into said square and passing through said perforation into a vertical spike hole in the tie, and a resilient gripping arm curved upwardly and sidewardly away from said shank at an oblique angle to 40 towards said rail and having its free end bent slightly downwardly to engage the rail flange at a point spaced from said shank.

7. In a rail fastening, the combination with a wood tie and a rail supported thereon, of a 45 rail spike comprising a shank of substantially square cross-section driven into a vertical spike hole in said tie with two of its sides disposed at right angles to the longitudinal axis of the rail, and a resilient gripping arm curved upwardly and 50 sidewardly away from said shank at an oblique angle towards said rail and having its free end bent slightly downwardly to engage the rail flange at a point spaced from said shank.

8. A rail spike for securing railway rails to 55 wood ties, comprising a shank of substantially square cross-section to fit into a normal spike hole, and a resilient gripping arm curved upwardly and sidewardly away from said shank in a vertical plane disposed at an oblique angle to the 60 sides of the latter and having its free end bent slightly downwardly to engage a rail flange at a point spaced from the shank.

9. In a rail fastening, the combination with a rail and a wood tie of a tie plate disposed on 65 said tie having a center portion supporting the flange of the rail and a side portion provided with a polyangular perforation, four corners of said perforation corresponding to the corners of an imaginary square disposed with its sides at 70 an oblique angle to the longitudinal axis of the rail, and a rail spike comprising a shank of substantially square cross-section and a resilient gripping arm curved upwardly and sidewardly away from said shank in a vertical plane paral- 75

- 5   1. A tie plate for railway rails having a center portion to support the flange of a rail and a side portion provided with a polyangular perforation, four corners of said perforation corresponding to the corners of an imaginary square of a size to fit a normal spike shank of square cross-section and disposed with its sides at an oblique angle to the longitudinal axis of the plate.
- 10   2. A tie plate for railway rails having a center portion to support the flange of a rail and a side portion provided with a substantially square perforation fitting a normal spike shank of square cross-section and being disposed with its sides at an oblique angle to the longitudinal axis of the plate.
- 15   3. A tie plate for railway rails having a center portion to support the flange of a rail and a side portion provided with a substantially square perforation fitting a normal spike shank of square cross-section and being disposed with its sides at an oblique angle to the longitudinal axis of the plate.
- 20   4. A tie plate for railway rails having a center portion to support the flange of a rail and a side portion provided with a substantially square perforation fitting a normal spike shank of square cross-section and being disposed with its sides at an oblique angle to the longitudinal axis of the plate.
- 25   5. A tie plate for railway rails having its free end bent slightly downwardly to engage the rail flange at a point spaced from the shank, the latter passing through said perforation into a vertical spike hole in said tie and being secured by said four corners of the perforation against rotation in an angular position in which said gripping arm projects at an oblique angle towards said rail.
- 30   6. In a rail fastening, the combination with a wood tie and a rail supported thereon, of a rail spike comprising a shank of substantially square cross section driven into a vertical spike hole in said tie with its sides disposed at an oblique angle to the longitudinal axis of the rail, and a resilient gripping arm curved upwardly and sidewardly away from said shank in a vertical plane parallel to two sides of the shank and having its free end bent slightly downwardly to engage the rail flange at a point spaced from said shank.
- 35   7. A tie plate for railway rails having a center portion to support the flange of a rail and a side portion provided with a substantially square perforation fitting a normal spike shank of square cross-section and being disposed with its sides at an oblique angle to the longitudinal axis of the plate.
- 40   8. A tie plate for railway rails having a center portion to support the flange of a rail and a side portion provided with an octangular perforation, four corners of said perforation corresponding to the corners of an imaginary square of a size to
- 5   9. A tie plate for railway rails having a center portion to support the flange of a rail and a side portion provided with a substantially square perforation fitting a normal spike shank of square cross-section and disposed with its sides at an oblique angle to the longitudinal axis of the plate, and the four remaining corners of the perforation corresponding to the corners of a second imaginary square having the same size as said first square and being turned at an angle of 45° with respect thereto.
- 10   10. In a rail fastening for unidirectional traffic the combination with a plurality of wood ties and a rail supported thereon, of a plurality of rail spikes comprising shanks driven into vertical spike holes in said ties disposed along two parallel lines on either side of the rail flange, and resilient gripping arms curved upwardly and sidewardly away from said shanks and having their free ends bent slightly downwardly to engage the rail flange at points spaced from said shanks, the latter being held against rotation in angular positions, in which all said gripping arms project at an angle between 45 and 60° towards said rail with their free ends pointing in the longitudinal direction opposite to that of the traffic.
- 15   11. In a rail fastening for traffic in both directions, the combination with a plurality of wood ties and a rail supported thereon, of a plurality of rail spikes comprising shanks driven into vertical spike holes in said ties disposed along two parallel lines on either side of the rail flange, and resilient gripping arms curved upwardly and sidewardly away from said shanks and having their free ends bent slightly downwardly to engage the rail flange at points spaced from said shanks, the latter being held against rotation in angular positions in which said gripping arms project at an angle between 45 and 60° towards said rail, certain of said gripping arms pointing with their free ends in opposite longitudinal directions.
- 20   12. In a rail fastening for unidirectional traffic the combination with a plurality of wood ties and a rail supported thereon, of a plurality of rail spikes comprising shanks driven into vertical spike holes in said ties disposed along two parallel lines on either side of the rail flange, and resilient gripping arms curved upwardly and sidewardly away from said shanks and having their free ends bent slightly downwardly to engage the rail flange at points spaced from said shanks, the latter being held against rotation in angular positions, in which all said gripping arms project at an angle between 45 and 60° towards said rail with their free ends pointing in the longitudinal direction opposite to that of the traffic.
- 25   13. In a rail fastening for traffic in both directions, the combination with a plurality of wood ties and a rail supported thereon, of a plurality of rail spikes comprising shanks driven into vertical spike holes in said ties disposed along two parallel lines on either side of the rail flange, and resilient gripping arms curved upwardly and sidewardly away from said shanks and having their free ends bent slightly downwardly to engage the rail flange at points spaced from said shanks, the latter being held against rotation in angular positions in which said gripping arms project at an angle between 45 and 60° towards said rail, certain of said gripping arms pointing with their free ends in opposite longitudinal directions.

BERTHOLD KUCKUCK. 40
